UNITED STATES PATENT OFFICE.

MADGE M. LUSK, OF BROOKLYN, NEW YORK.

LID FOR WATER-CLOSETS.

1,304,336.

Specification of Letters Patent.

Patented May 20, 1919.

Application filed March 21, 1918. Serial No. 223,716.

To all whom it may concern:

Be it known that I, MADGE M. LUSK, a citizen of the United States, and a resident of the city of New York, borough of Brooklyn, in the county of Kings and State of New York, have invented a new and Improved Lid for Water-Closets, of which the following is a full, clear, and exact description.

10 The object of the invention is to provide a new and improved lid for water closets arranged to keep the water closet in sanitary condition by practically a continuous disinfection thereof. Another object is to provide 15 a disinfecting means which is simple and durable in construction and which can be cheaply manufactured and readily used.

In order to produce the desired result, use is made of a light frame adapted to rest on 20 and to cover the seat of a water closet, and a disinfectant holder mounted on the said frame and extending in the opening of the seat.

A practical embodiment of the invention 25 is represented in the accompanying drawings forming a part of this specification in which similar characters of reference indicate corresponding parts in all the views.

Figure 1 is a plan view of the lid;

30 Fig. 2 is a front edge view of the same as applied to a water closet, the seat of which is shown in section;

Fig. 3 is an enlarged sectional side elevation of a portion of the lid on the line 3—3 35 of Fig. 1.

The frame 10 of the lid is preferably made of cardboard or other suitable stiff material, and the said frame in outline is shaped corresponding to the seat 11 of a water closet 40 12 having the usual cover 13. The frame 10 is adapted to rest on the seat 11 so as to cover the same, as plainly indicated in Fig. 2. The frame 10 is provided with a central opening 15 in which extends a disinfectant

45 holder 16 having a perforate top 17 and a perforate bottom 18 with the margins thereof secured to the frame 10. Between the top 17 and the bottom 18 is held an absorbent material 19 such as cotton or the like 50 adapted to be saturated with a suitable disinfectant of liquid, powder or other form.

It will be noticed that the disinfectant material completely fills the opening 15 of the frame 10 and hence the escape of germs by way of the said opening is prevented and 55 the water closet is practically continually disinfected. The frame 10 is provided at its margin with a suitable hanger 20 to permit of conveniently and temporarily hanging up the lid during the time the water closet is 60 used, it being understood that the user of the water closet returns the lid after use of the water closet. It will be noticed that the lid is practically continually in use except during the short time the water closet is 65 used, and the lid can be readily temporarily removed from the seat and replaced as described, and the disinfectant can be replenished from time to time thus rendering the lid exceedingly effective for disinfecting 70 purposes at all times.

The frame 10 is preferably covered at the top, bottom and outer edge by a covering 21 of enameled or glazed paper which extends over the marginal edges of the top 17 75 and the bottom 18 so as to give an exceedingly neat appearance to the lid.

It is understood that the top 17 and the bottom 18 is of perforate material such as gauze, wire netting, or the like, but I do not 80 limit myself to any particular perforate material.

Having thus described my invention, I claim as new and desire to secure by Letters Patent:—

1. As an article of manufacture, a lid for water closet seats, comprising a flat annular frame having a central opening and adapted to rest on and cover the seat of the water closet, and a disinfectant holder including 90 perforate top and bottom sheets the margins of which are secured to the upper and lower faces of the annular frame and cover the central opening thereof, and an absorbent material contained between the upper and 95 lower sheets of the holder.

2. As an article of manufacture, a lid for water closet seats, comprising a light frame adapted to rest on and to cover the seat of a water closet, the said frame having an opening, a disinfecting holder having a perforate 100 top and a perforate bottom and attached to

the frame and extending across the opening thereof, and an absorbent material contained in the holder.

3. As an article of manufacture, a lid for 5 water closet seats comprising a light frame adapted to rest on and to cover the seat of a water closet, the said frame having an opening, a disinfectant holder having a perforate

top and a perforate bottom and attached to the frame and extending across the opening thereof, an absorbent material contained in the holder, and a covering for the top and bottom of the frame and extending over the margins of the said perforate top and bottom of the holder.¹⁰

MADGE M. LUSK.
